UNITED STATES PATENT OFFICE.

KARL D. SMITH, OF BATTLE CREEK, MICHIGAN, ASSIGNOR TO UNION STEAM PUMP COMPANY, OF BATTLE CREEK, MICHIGAN.

VACUUM-PUMP.

1,384,927.

Specification of Letters Patent. Patented July 19, 1921.

Application filed September 7, 1915. Serial No. 49,274.

To all whom it may concern:

Be it known that I, KARL D. SMITH, a citizen of the United States, residing at Battle Creek, county of Calhoun, State of Michigan, have invented certain new and useful Improvements in Vacuum-Pumps, of which the following is a specification.

This invention relates to improvements in vacuum pumps.

10 My improvements are especially designed by me for embodiment in dry system pumps, that is, pumps for handling air only, and I have illustrated my improvements as I have embodied them for such purposes.

15 The main objects of my invention are:

First, to provide an improved pump in which the passages and ports, valve seats, and valve chambers are easily formed and are readily accessible.

20 Second, to provide an improved pump in which the valves are in the form of flat annular steel disks with low lift or movement, making it practical to operate the machine at high speeds without noticeable noise, and at the same time one having a 25 large free portage.

Third, to provide an improved pump which retains its efficiency when operated at high speeds.

20 Further objects, and objects relating to structural details, will definitely appear from the detailed description to follow.

I accomplish the objects of my invention by the devices and means described in the 35 following specification. The invention is clearly defined and pointed out in the claims.

A structure which is a preferred embodiment of my invention is clearly illustrated 40 in the accompanying drawing, forming a part of this specification, in which:

Figure I is a side view of a pump embodying the features of my invention, a portion of the fly wheel being broken away.

45 Fig. II is a vertical central section on a line corresponding to line 2—2 of Fig. I, the crank shaft, connecting rod, and piston pin being shown in full lines.

Fig. III is a horizontal section on a line 50 corresponding to line 3—3 of Fig. II through the air intake passage.

Fig. IV is a horizontal section on a line 55 corresponding to line 4—4 of Fig. II, showing the arrangement of the inlet passages and the cylinder ports.

Fig. V is a horizontal section on a line corresponding to line 5—5 of Fig. II showing the arrangement of the discharge passages.

Fig. VI is a detail vertical section on a 60 line corresponding to line 6—6 of Fig. V.

Fig. VII is a perspective view of one of the valves.

In the drawing similar reference characters refer to similar parts throughout the 65 several views, and the sectional views are taken looking in the direction of the little arrows at the ends of the section lines.

Referring to the drawings, the cylinder 1 is mounted upon the crank case 2 to open 70 therein. The crank case is provided with a suitable supporting base 3. The cylinder has an annular intake passage 4 at its outer end, with inlet openings 5 and a plurality of discharge openings 6 open at the end of the 75 cylinder, which is faced off flat to receive the cylinder head. The cylinder head is built up of plate-like sections or members 7, 8 and 9, the member 7 being the inner member or that adjacent the cylinder, the member 8 80 an intermediate member, and the member 9 the outer member of the head. These members, when assembled, are secured to the cylinder by means of the head bolts 10. The inner member 7 is plate-like in form and is 85 provided with a plurality of radially disposed inlet passages 11 communicating with the discharge passages 6 of the intake passage 4. The member 7 has an annular valve seat 12 for the inlet valve 13 on its inner 90 face. The passages 11 open into this valve seat to be closed by the valve when it is seated, as shown in Fig. II. The inner head member 7 is also provided with cylinder ports 14 grouped within the inlet passages. 95 See Figs. II and IV. The intermediate member 8 has an annular recess 15 in its inner face constituting a chamber for the inlet valve 13. This chamber embraces the cylinder ports 14 and also the inlet ports 11. 100 The intermediate member 8 has an annular valve seat 16 on its outer face for the annular discharge valve 17 and is provided with discharge passages 18 opening into the valve seat. The outer head member 9 has a recess 19 in its inner face constituting a chamber for the discharge valve and is provided with a central discharge opening 20 adapted to receive a discharge pipe.

The valves 13 and 17 are in the form of 110

annular disks of steel. The diameters of the valves are somewhat less than the diameters of the valve chambers, so as to allow the air to pass around and through the 5 valves. The larger diameters of the valve chambers also permit limited lateral movement of the valves, so that the valves and the valve seats wear evenly, and also it prevents any binding or wedging action, the 10 valve floating freely in the valve chambers.

I preferably provide seating springs 21 disposed at intervals around the valves. The head members 8 and 9 have bore-like seats 22 therein adapted to receive and support 15 the springs. These valves are comparatively thin, but at the same time are sufficiently thick to prevent any springing of the valves and to insure durability.

By thus forming the head of sections or 20 members the ports and passages may be readily formed and the parts conveniently assembled, making the structure economical to produce and also providing free portage for the air. The valves have but little lift 25 and are practically noiseless in operation. At the same time, the structure may be operated at high speed without impairing the efficiency of the pump, which not infrequently occurs in pumps of this character 30 owing to the valves "fluttering" and failing to seat properly at high speeds.

The piston 23 is comparatively long and has a bearing portion 24 at its inner end which keeps the piston in line and also prevents 35 oil being carried above the cylinder.

The connecting rod 25 is connected to the cross head pin 26 oscillating in the bearings 27 on the piston, although this may be varied as desired.

40 The crank shaft 28 is supported in suitable bearings in the bearing members 29 and 30 arranged in alined openings in the crank case.

The bearing member 29 is extended to 45 support the fly-wheel end of the crank shaft and is provided with oil passages 31 adapted to receive the splash from the crank arms and deliver to the bearing. A return passage 32 is provided for the lubricant.

50 To insure efficient lubricating of the crank shaft an oil cup 33 is provided, which may be filled with waste, permitting the lubricant to drip into the annular recess 34 below the cup.

55 As is well understood, it is necessary to provide so-called "breathing" openings for the crank case, and to prevent the escape of the lubricant through these openings I provide the bearing member 30 with a baffle 60 chamber 35 having a conical inner wall 36 provided with a central opening 37. About this opening is an inwardly projecting flange 38 and an outwardly projecting flange 39. The outer wall 40 of this baffle chamber has 65 annular flanges 41 and 42, the flanges being

concentric with the flange 39 of the inner wall and the flange 43 thereof. These flanges provide a zig-zag baffle passage so that the oil is collected from the air before it reaches the openings 44 of the baffle chamber. The baffle chamber is provided with a small opening 45 at the bottom so that the collected oil may drip back into the oil well 46 of the crank case. I, however, call attention to the embodiment of my invention 75 shown in my copending application, Serial No. 152,810, filed March 6, 1917.

Having thus described my invention, what I claim as new and desire to secure by Letters Patent is:

1. In a structure of the class described, the combination of a cylinder having an annular intake passage at its outer end provided with discharge openings at the end of the cylinder, a cylinder head comprising an inner plate-like head member having an annular inlet valve seat on its outer face and a plurality of radially disposed inlet passages communicating with said discharge openings of said intake passage and opening into said valve seat, and a plurality of cylinder ports grouped within said inlet passages, an intermediate plate-like head member having an annular discharge valve seat on its outer face and an annular recess in its inner face constituting an inlet valve chamber into which said cylinder ports open, said intermediate head member being also provided with discharge ports opening into said discharge valve seat, 100 an outer head member having a recess in its inner face constituting a discharge valve chamber, said chamber being provided with a discharge opening, annular disk-like valves arranged in said valve chambers to 105 coact with said valve seats, the diameters of said valves being such as to permit a limited lateral movement on their seats and the passage of air around and through the valves, and coiled seating springs for said valves, 110 said intermediate and outer head members being provided with bore-like seats for said springs alined with said valves.

2. In a structure of the class described, the combination of a cylinder having an annular intake passage at its outer end provided with discharge openings at the end of the cylinder, a cylinder head comprising an inner plate-like head member having an annular inlet valve seat on its outer face and a plurality of radially disposed inlet passages communicating with said discharge openings of said intake passage and opening into said valve seat, and a plurality of cylinder ports grouped within said inlet passages, an intermediate plate-like head member having an annular discharge valve seat on its outer face and an annular recess in its inner face constituting an inlet valve chamber into which said cylinder ports open, said intermediate 115 and outer head members being provided with bore-like seats for said springs alined with said valves.

mediate head member being also provided with discharge ports opening into said discharge valve seat, an outer head member having a recess in its inner face constituting 5 a discharge valve chamber, said chamber being provided with a discharge opening, and annular disk-like valves arranged in said valve chambers to coact with said valve seats, the diameters of said valves being such 10 as to permit a limited lateral movement on their seats and the passage of air around and through the valves.

3. In a structure of the class described, the combination of a cylinder having an annular 15 intake passage at its outer end, a cylinder head comprising an inner head member having an annular inlet valve seat on its outer face and a plurality of inlet passages communicating with said intake passage and 20 opening into said valve seat, and a plurality of cylinder ports, an intermediate head member having an annular discharge valve seat on its outer face and an annular recess in its inner face constituting an inlet valve 25 chamber into which said cylinder ports open, said intermediate head member being also provided with discharge ports opening into said discharge valve seat, an outer head member having a recess in its inner face constituting 30 a discharge valve chamber, said chamber being provided with a discharge opening, annular disk-like valves arranged in said valve chambers to coact with said valve seats, and coiled seating springs for 35 said valves, said intermediate and outer head members being provided with bore-like seats for said springs alined with said valves.

4. In a structure of the class described, the combination of a cylinder having an annular 40 intake passage at its outer end, a cylinder head comprising an inner head member having an annular inlet valve seat on its outer face and a plurality of inlet passages communicating with said intake passage and 45 opening into said valve seat, and a plurality of cylinder ports, an intermediate head member having an annular discharge valve seat on its outer face and an annular recess in its inner face constituting an inlet valve 50 chamber into which said cylinder ports open, said intermediate head member being also provided with discharge ports opening into said discharge valve seat, an outer head member having a recess in its inner face constituting 55 a discharge valve chamber, said chamber being provided with a discharge opening, and annular disk-like valves arranged in said valve chamber to coact with said valve seats.

5. In a structure of the class described, the combination of a cylinder, a cylinder head comprising an inner head member having an annular inlet valve seat on its outer face and a plurality of inlet passages opening 60 into said valve seat, and a plurality of cyl-

inder ports, an intermediate head member having an annular discharge valve seat on its outer face and an annular recess in its inner face constituting an inlet valve chamber into which said cylinder ports open, said 70 intermediate head member being also provided with discharge ports opening into said discharge valve seat, an outer head member having a recess in its inner face constituting a discharge valve chamber, said chamber being 75 provided with a discharge opening, annular disk-like valves arranged in said valve chambers to coact with said valve seats, and coiled seating springs for said valves, said intermediate and outer head members being 80 provided with bore-like seats for said springs alined with said valves.

6. In a structure of the class described, the combination of a cylinder, a cylinder head comprising an inner head member having an annular 85 inlet valve seat on its outer face and a plurality of inlet passages opening into said valve seat, and a plurality of cylinder ports, an intermediate head member having an annular discharge valve seat on its outer face and an annular recess in its inner face constituting an inlet valve chamber into which said cylinder ports open, said 90 intermediate head member being also provided with discharge ports opening into said discharge valve seat, an outer head member having a recess in its inner face constituting a discharge valve chamber, said chamber being provided with a discharge opening, and annular disk-like valves arranged in said 95 valve chambers to coact with said valve seats.

7. In a structure of the class described, the combination of a cylinder, a closed crank case into which the cylinder opens, said crank case being provided with a splash oil well, a piston, a crank shaft, said crank shaft case having alined openings adapted to receive crank shaft bearing members, and crank shaft bearing members, one of said bearing members having a baffle chamber 105 therein open to the atmosphere and provided with a conical inner wall having a central opening therein with inwardly and outwardly projecting baffle flanges about the opening and a surrounding annular 110 flange, the outer wall having inwardly projecting annular flanges concentric with the flanges of the inner wall and disposed to coact with said flanges of said inner wall to provide zig-zag baffle passages.

8. In a structure of the class described, the combination of a cylinder, a piston, a crank case into which the cylinder opens, said crank case being provided with a splash oil well and with a baffle member opening, and 120 a baffle member arranged in said crank case opening and having a baffle chamber therein open to the atmosphere and provided with a conical inner wall having a central opening therein with inwardly and outwardly 125

- projecting baffle flanges about the opening and a surrounding annular flange, the outer wall having inwardly projecting annular flanges concentric with the flanges of the inner wall and disposed to coact with said flanges of said inner wall to provide zig-zag baffle passages.
9. In a structure of the class described, the combination of a cylinder, a cylinder head comprising an inner head member having an annular inlet valve seat on its outer face and a plurality of inlet passages opening into said valve seat, and a plurality of cylinder ports, an intermediate head member having an annular discharge valve seat on its outer face and discharge ports opening into said discharge valve seat, said inner and intermediate head members being formed to inclose between them an annular inlet valve chamber into which said cylinder ports open, an outer head member having a recess in its inner face constituting a discharge valve chamber, said chamber being provided with a discharge opening, annular disk-like valves arranged in said valve chambers to coact with said valve seats, and coiled seating springs for said valves, said intermediate and outer head members being provided with bore-like seats for said springs alined with said valves.
10. In a structure of the class described, the combination with a cylinder, of a head therefor comprising a pair of superimposed head members, the inner head member having a valve seat on its outer face, a plurality of inlet ports opening into said valve seat, and a plurality of cylinder ports, said head members being formed to inclose between them an inlet valve chamber into which the cylinder ports open, the superimposed member being provided with a discharge port opening into said inlet valve chamber, a valve for said discharge port, and a disk-like inlet valve.
11. In a structure of the class described, the combination of a cylinder, a cylinder head comprising a pair of superimposed head members formed to inclose between them an annular inlet valve chamber, the inner head member having an annular inlet valve seat in its outer face and a plurality of inlet passages opening into said valve seat and a plurality of cylinder ports opening into said inlet valve chamber, the superimposed head member being provided with an annular discharge valve seat and discharge ports opening into said valve seat and to said inlet valve chamber, annular disk-like valves arranged to coact with said valve seats, and seating springs for said valves.
12. In a structure of the class described, the combination of a cylinder, a cylinder head comprising a pair of superimposed head members, the inner head member having an annular inlet valve seat in its outer face and a plurality of inlet passages opening into said valve seat and a plurality of cylinder ports, the superimposed head member being provided with a discharge port, said head members being formed to inclose between them an annular inlet valve chamber into which said cylinder and discharge ports open, a valve for said discharge port, and an annular disk-like valve arranged in said inlet valve chamber to coact with said valve seat.
13. In a structure of the class described, the combination of a cylinder, a cylinder head comprising an inner head member having an annular inlet valve seat in its outer face and a plurality of inlet passages opening into said valve seat and a plurality of cylinder ports, a second head member provided with an annular discharge valve seat and discharge ports opening into said discharge valve seat, said head members being formed to inclose between them an annular inlet valve chamber into which said cylinder ports open, annular disk-like valves arranged in said valve chambers to coact with said valve seats, and seating springs for said valves.
14. In a structure of the class described, the combination of a cylinder, a cylinder head comprising an inner head member having an annular inlet valve seat on its outer face and a plurality of inlet passages opening into said valve seat and a plurality of cylinder ports, a second head member having an annular discharge valve seat and discharge ports opening into said discharge valve seat, said head members being formed to inclose between them an annular inlet valve chamber into which said cylinder ports open, and annular disk-like valves coacting with said seats.
15. In a structure of the class described, the combination with an open ended cylinder, of a cylinder head detachably secured thereto and comprising superimposed members coacting to form an inlet valve chamber, an inlet port communicating with said inlet valve chamber, a valve in said inlet valve chamber, a port establishing communication between said inlet valve chamber and said cylinder, the superimposed member being provided with a discharge valve chamber, and ports establishing communication between said inlet valve chamber and said discharge valve chamber, a valve in said discharge valve chamber, and means for urging said valves to their closed position.
16. In a structure of the class described, the combination with a cylinder, of a head therefor comprising superimposed head members, the inner head member having an annular inlet valve seat on its outer face, a plurality of inlet passages opening into said valve seat, and a plurality of cylinder ports, the superimposed head member having an

- annular discharge valve seat on its outer face and discharge ports opening into said discharge valve seat, said head members being formed to inclose between them an inlet valve chamber into which said cylinder and discharge ports open, and annular disk-like valves arranged to coact with said valve seats, one of said head members being provided with a central cylindrical part constituting a guide for said inlet valve.
17. In a structure of the class described, the combination with a cylinder, of a head therefor comprising superimposed head members, the inner head member having an annular inlet valve seat on its outer face, a plurality of inlet passages opening into said valve seat, and a plurality of cylinder ports, the superimposed head member having a discharge port, said head members being formed to inclose between them an inlet valve chamber into which said cylinder and discharge ports open, a valve for said discharge port, and an annular disk-like inlet valve arranged to coact with said inlet valve seat, one of said head members being provided with a cylindrical part constituting a guide for said inlet valve.
18. In a structure of the class described, the combination with a cylinder, of a head therefor comprising superimposed head members, the inner head member having a valve seat on its outer face, a plurality of inlet ports opening into said valve seat, and a plurality of cylinder ports, said head members being formed to inclose between them an inlet valve chamber into which the cylinder ports open, the superimposed member being provided with a discharge port opening into said inlet valve chamber, a valve for said discharge port, and a disk-like inlet valve.
19. In a structure of the class described, the combination of a cylinder, a cylinder head comprising superimposed head members formed to inclose between them an annular inlet valve chamber, the inner head member having an annular inlet valve seat in its outer face and a plurality of inlet passages opening into said valve seat and a plurality of cylinder ports opening into said inlet valve chamber, the superimposed head member being provided with an annular discharge valve seat and discharge ports opening into said valve seat and to said inlet valve chamber, annular disk-like valves arranged to coact with said valve seats, and seating springs for said valves.
20. In a structure of the class described, the combination of a cylinder, a cylinder head comprising superimposed head members, the inner head member having an annular inlet valve seat in its outer face and a plurality of cylinder ports, the superimposed head member being provided with a discharge port, said head members being formed to inclose between them an annular inlet valve chamber into which said cylinder and discharge ports open, a valve for said discharge port, and an annular disk-like inlet valve arranged to coact with said valve seats, one of said head members being provided with a central cylindrical part constituting a guide for said inlet valve.
21. In a structure of the class described, the combination of a cylinder, a cylinder head comprising an inner head member having an annular inlet valve seat in its outer face and a plurality of inlet passages opening into said valve seat and a plurality of cylinder ports, a second head member provided with an annular discharge valve seat and discharge ports opening into said discharge valve seat, said head members being formed to inclose between them an annular inlet valve chamber into which said cylinder ports open, annular disk-like valves arranged in said valve chambers to coact with said valve seats, and seating springs for said valves.
22. In a structure of the class described, the combination of a cylinder, a cylinder head comprising an inner head member having an annular inlet valve seat on its outer face and a plurality of inlet passages opening into said valve seat and a plurality of cylinder ports, a second head member having an annular discharge valve seat and discharge ports opening into said discharge valve seat, said head members being formed to inclose between them an annular inlet valve chamber into which said cylinder ports open, and annular disk-like valves co-acting with said seats.
23. In a structure of the class described, the combination of a cylinder, a head comprising an inner head member having an annular inlet valve seat on its outer face, and a plurality of inlet passages opening into said valve seat and a plurality of cylinder ports, a superimposed head member having an annular discharge valve seat and discharge ports opening into said discharge valve seat, said head members being formed to inclose between them a valve chamber into which said cylinder and discharge ports open, a cap member, said cap member and superimposed head member being formed to inclose between them a discharge valve chamber, annular disk-like valves arranged in said valve chambers to coact with said valve seat, and seating springs for said valves, said superimposed and cap members being adapted to support said springs.
24. In a structure of the class described, the combination with an open ended cylinder, of a head detachably secured thereto and provided with three superimposed chambers, the lower chamber constituting an inlet chamber, the upper chamber constituting a discharge valve chamber, and the intermediate chamber constituting an inlet valve chamber, said head being provided with a discharge port, said head members being formed to inclose between them an annular inlet valve chamber into which said cylinder and discharge ports open, a valve for said discharge port, and an annular disk-like inlet valve arranged to coact with said valve seats, one of said head members being provided with a central cylindrical part constituting a guide for said inlet valve.

with inlet, outlet, and cylinder ports establishing communication between said inlet valve chamber and said inlet chamber, discharge chamber, and cylinder, respectively, and valves for closing the upper ends of said inlet ports and said discharge ports.

25. In a structure of the class described, the combination with an open ended cylinder, of a head therefor comprising an inner member and an outer member coacting to provide an inlet valve chamber, a valve seat formed in the bottom of said inlet valve chamber, an inlet valve, said inner member being provided with inlet ports communicating with said inlet valve chamber and opening into said valve seat, and a port forming communication between said inlet valve chamber and said cylinder, said outer member being provided with discharge ports communicating with said inlet valve chamber, and a valve for said discharge ports, substantially as described.

26. In a structure of the class described, the combination with an open ended cylinder, of a head detachably secured thereto provided with two chambers, one of said chambers constituting a discharge valve chamber and the other of said chambers constituting an inlet valve chamber, a valve seat in each of said chambers, inlet ports communicating with said inlet valve chamber and opening into the valve seat therein,

discharge ports extending from said inlet valve chamber to said discharge valve chamber and opening into the valve seat in said discharge chamber, and a valve for each of said valve seats, said head being provided with a port establishing communication between said inlet valve chamber and said cylinder, substantially as described.

27. In a structure of the class described, the combination with an open ended cylinder, of a cylinder head detachably secured thereto and comprising superimposed members coacting to form an inlet valve chamber, an inlet port communicating with said inlet valve chamber, a valve in said inlet valve chamber, a port establishing communication between said inlet valve chamber and said cylinder, the superimposed member being provided with a discharge valve chamber, and ports establishing communication between said inlet valve chamber and said discharge valve chamber, a valve in said discharge valve chamber, and means for urging said valves to their closed position.

In witness whereof, I have hereunto set my hand and seal in the presence of two witnesses.
